UNITED STATES PATENT OFFICE.

OTTO J. KUHLKE, OF AKRON, OHIO, ASSIGNOR TO THE KUHLKE MACHINE COMPANY,
OF AKRON, OHIO, A CORPORATION OF OHIO.

COLLAPSIBLE CORE.

Application filed August 23, 1922. Serial No. 584,314.

To all whom it may concern:

Be it known that I, Otto J. KUHLKE, a citizen of the United States, and a resident of Akron, county of Summit, State of Ohio, have invented certain new and useful Improvements in Collapsible Cores, of which the following is a specification.

The object of this invention is to construct a form of core for use in the manufacture of tires, which is capable of being collapsed without being removed from the stand or machine on which it is mounted. The core, as shown, is designed to embody a simple and easily operated core construction which does not necessitate a complicated mechanism to break it down or collapse it.

One form only of the invention is shown in this application, it being obvious that other forms may be devised which embody the general principles set forth without departing from the spirit of the invention or sacrificing any of the benefits thereof, and such as fall within the scope of the invention are intended to be covered herein.

In the drawings:

Figure 1 is a side elevation of the improved collapsible core, the core in assembled position being shown in full lines, and in collapsed position in dotted lines;

Figure 2 is a plan view of the core collapsed;

Figure 3 is a plan view of the core assembled;

Figure 4 is a detail of the hinge construction; and

Figure 5 is a section through the shaft.

The core perfected by me is divided into a plurality of sections, one of which is rigid with respect to the shaft on which it is mounted and the others are connected to the rigid section so that the various sections are not separable from the rigid section, but may be moved into position so that the tire can be removed.

The problem which has presented itself to designers of cores of this general type has been the provision of some means by which the several core sections can be moved and contained within the circumference of the annular, unstretchable beads on the inner edges of the tire, so that the latter could be removed. In prior constructions this has been sought to be done by constructing one or more sections so that they can

be detached from the remaining sections and removed from within the circumference of the tire bead to permit the remaining sections to be collapsed within the bead line.

In my improved collapsible core, however, the sections of the core are so arranged and connected that in the collapsing of the core, none of the sections are detached from one another, but all are brought within the area of the bead circumference.

In tires of standard construction at the present time, for example, 35 x 5 tires, the diameter of the bead of the tire is approximately 25 inches, and in order to enable the tire to pass over the sections in collapsed form, it is necessary to remove the sections laterally to the proper extent. This has been accomplished, as will be seen from the description of the invention, without detaching any of the sections, but so hinging them that they can be collapsed in substantially helical form, in which form the tire can be removed.

In the drawings, the numeral 1 represents the shaft on which the core is supported, 2 a flanged sleeve mounted on the end of the shaft.

The core comprises a rigid section 3 which is carried on arms 4 that converge to a hub 5 adapted to be passed over the sleeve and secured to the flange by bolts 6. In order to complete the annular tire form or core, it is divided into a plurality of sections, here shown as four in number, arranged in two groups of two each on either side of a major cut or division line 7, shown diametrically opposite the rigid section 3. The number of sections, the grouping thereof, and the arrangement of the principal cut may be varied as desired within the scope and general principles of the invention.

The major cut 7 is arranged on a curved line, the general plane of which is at an angle to the plane of the core, for reasons that will be apparent upon further description of the invention. This cut is obtained by placing two complementary plates 8 and 8^a in the mold at the time of casting the core.

The right hand group of core sections are numbered 9 and 10 from the cut 7 and are divided from each other and from the stationary section by straight radial cuts. The left hand group are numbered similarly 11 and 12 and are similarly divided. When

the core sections are in position to form the complete annular core, the sections 9 and 11 are held together to maintain the core in position by any suitable means. That 5 shown herein comprises a plate 13 which is secured to the inner periphery of the core and extends across the split, being provided at its outer end with a lug 14 which is received in a corresponding recess in the inner periphery of the section 11. The plate 10 is secured in locking position by a swinging link 15 and an eccentric locking lever 16.

When it is desired to collapse the core, the 15 fastening is released and the section 9 is first swung toward the center of the core, the inward movement of the section being regulated by a stop 17 adapted to contact the section 10. The section 9 swings downwardly on a hinge 18 between the sections 9 20 and 10, the pintle 19 of which hinge is arranged at an inclined angle to the plane of the core so that the section 9 swings outwardly from the plane of the core.

The section 10 is now swung toward the 25 center of the core and outwardly on its hinge 20 which is so arranged that that section follows outwardly, serving to move the section 9 further outwardly from the plane of the core or rigid section 3, the inward 30 limit of movement of the section 10 being determined by the stop 21.

The section 11 is now moved inwardly on its hinge 22 against stop 23, but it will be observed that the pintle 24 of this hinge is 35 inclined in the opposite direction from the hinges 18 and 20 so that the section 11 moves outwardly on the opposite side of the core plane from the sections 9 and 10. The section 12 now follows in the same manner 40 about its hinge 25 with stop 26.

The collapsed position of the core is shown in Figure 2 and it will be noted that the core is in substantially the shape of a helix, the two arms of which extend on opposite sides of the rigid or stationary section 3. The space between the nearest points of the two sections is preferably large enough to permit the tire to be inserted between them to remove the lower portion 50 thereof from the rigid section.

So far as known to me, I am the first to 55 construct and arrange a collapsible tire core so that all of the sections thereof may be moved into position to permit the removal of tires with relatively small bead diameters, without disconnecting one of the sections from the balance. This is obviously a great advantage in building tires. I am also the first to construct a sectional core 60 in which the several sections are so connected together that in moving them to collapsed position the core will assume a substantially helical form. The invention is not limited to the exact arrangement of 65 sections as other equivalent arrangements

may be made without departing from the principles of the invention. The number and division lines of the sections may be altered and other modifications can be resorted to.

What I claim is:

1. In a collapsible core construction, a plurality of movable sections, said sections being hinged together to form a helix in collapsed position.

2. In a collapsible core construction, a group of movable core sections, said sections being hinged together end to end to move toward the center of the core and outwardly from the plane of the core.

3. In a collapsible core construction, groups of movable core sections, certain of said sections which are adjacent to one another being hinged together so as to move in a group toward the center line of the core 85 and outwardly from the plane of the core.

4. In a collapsible core construction, two groups of movable core sections, said sections being hinged together so as to move in groups toward the center line of the core 90 and outwardly in opposite directions from the plane of the core.

5. In a collapsible core, a plurality of movable core sections which are hinged together, the axis of the hinge being at an inclined angle to the plane of the core.

6. In a collapsible core, a rigid section and a plurality of movable core sections which are hinged together, the axes of the hinges being at an inclined angle to the plane 100 of the core.

7. In a collapsible core, a rigid section and a plurality of movable core sections which are hinged together in groups at the ends of the rigid section, the hinges of the 105 said groups being at inclined angles to the plane of the core.

8. In a collapsible core, a rigid section and a plurality of movable core sections which are hinged together in groups at the 110 ends of the rigid section, the hinges of the said groups being at oppositely inclined angles with respect to the plane of the core.

9. In a collapsible core, a rigid section and a group of movable core sections which are hinged together to form an approximate helix in collapsed position.

10. In a collapsible core, a rigid section and a group of movable sections, said movable sections being hinged to the end of the 120 rigid section and hinged together to move toward the center line of the core and outwardly from the plane of the core.

11. In a collapsible core, a rigid section and a plurality of movable core sections 125 which are hinged together, the axis of the hinge being arranged at an inclined angle to the plane of the core.

12. In a collapsible core, a plurality of core sections which are all connected to-

- gether to swing toward the center of the core and at the same time outwardly from the plane of the core.
13. In a collapsible core, a plurality of core sections which are arranged in two groups, all connected together to swing toward the center of the core, the said groups moving apart parallel to the axis of the core.
14. In a collapsible core, a plurality of movable core sections and a rigid section, the movable core sections being mounted to swing toward the center of the core and at the same time outwardly from the plane of the core.
15. In a collapsible core, a plurality of movable core sections and a rigid core section, the movable core sections being arranged to swing toward the center of the core and outwardly along the axis of the core to a position outside the plane of the core.
16. In a collapsible core, a rigid core section and a plurality of movable core sections, said movable core sections being arranged in two groups, the sections of each group being arranged to swing toward the center of the core and outwardly along the axis of the core to a position outside the plane of the core.
17. In a collapsible core, a rigid core section and a plurality of movable core sec-
- tions, said movable core sections being arranged in two groups, the sections of each group being arranged to swing toward the center of the core and outwardly in opposite directions from the plane of the core.
18. In a collapsible core, a plurality of core sections hinged together and divided by a major cut, the hinges between said sections being inclined to the plane of the core so that the core may be wound into a helix of smaller diameter than the inner periphery of the core.
19. A collapsible core divided into a plurality of sections, a single pivot for one of said sections arranged at an angle to the plane of the core so that it will move inwardly toward the axis of the core and at the same time outwardly from the plane of the core.
20. A collapsible core divided into a plurality of sections, a section being hinged to move inwardly toward the center of the core, the axis of said hinge being at an inclined angle to the plane of the core.
21. A collapsible core divided into a plurality of sections, a section being attached to its next adjacent section so that in collapsing the core it is compelled to shift in a single movement toward the center of the core and outwardly from the plane thereof.

OTTO J. KUHLKE.
